Atty.

UNITED STATES PATENT OFFICE.

HANS RICHARD HAERTEL, OF FRANKLIN, MASSACHUSETTS, ASSIGNOR OF FORTY-NINE ONE-HUNDREDTHS TO F. H. APPLETON & SON, INC., OF BOSTON, MASSACHUSETTS, A CORPORATION OF MASSACHUSETTS.

STRAINER.

1,286,297.

Specification of Letters Patent.

Patented Dec. 3, 1918.

Application filed February 16, 1918. Serial No. 217,986.

To all whom it may concern:

Be it known that I, HANS RICHARD HAERTEL, a subject of the Emperor of Germany, and a resident of Franklin, in the county of Norfolk and State of Massachusetts, have invented certain new and useful Improvements in Strainers, of which the following is a specification.

This invention relates to strainers and 10 more particularly to the strainer heads of machines for straining plastic material, such as rubber and similar substances, the principal object of the invention being to simplify the construction of said strainer where- 15 by the screens may be quickly changed when desired and injury thereto when in use will be effectually prevented.

Another object of the invention is to provide a construction of strainer head in which 20 the churning and overheating of the stock will be entirely obviated, thus preventing any decrease in the tensile strength and elasticity of the material.

A further object of the invention is the 25 provision of means whereby lumps in the material may be broken up or removed and in this manner cause the material to be uniform.

The invention consists of a head which 30 may be attached to or formed upon any existing form of straining or tubing machine, and which is provided with a cone-shaped strainer of fine mesh superimposed upon a cone-shaped support removable from and 35 adjustable in the delivery opening of said head.

The invention further consists of serrating the wall of the delivery opening thereby breaking up the lumps passing through 40 said opening, and retarding the outer portion of the material as it passes between said serrated wall and the cone screen.

The invention further consists in providing means whereby the unstrained portion 45 of the material may be collected and forced back into the source of supply.

The invention further consists in certain 50 novel features of construction and arrangement of parts which will be thoroughly understood by reference to the description of the drawings and to the claims to be hereinafter given.

For the purpose of illustrating the invention one preferred form thereof is illustrated

in the drawings, this form having been 55 found to give satisfactory and reliable results, although it is to be understood that the various instrumentalities of which the invention consists can be variously arranged and organized and the invention is not limited to the precise arrangement and organization of these instrumentalities as herein shown and described, except as required by the scope of the appended claims.

Of the drawings:

Figure 1 represents a section of a strainer head embodying the principles of the present invention, and

Fig. 2 represents an end elevation of the same with the cone shaped strainer and its 70 support removed from the discharge opening.

Similar characters designate like parts throughout the several figures of the drawings.

In the drawings 10 is a cylinder forming a part of a straining machine adapted to strain plastic material such, for instance, as rubber.

Within the cylinder 10 is a revoluble shaft 80 11 having formed thereon or secured thereto a screw 12 adapted to force the plastic material within said cylinder 10 toward the discharge end of said cylinder.

This discharge end of the cylinder is provided with an annular chamber 13 to which a temperature regulating medium may be admitted through the pipe 14.

The inner wall 15 of the discharge opening is inclined inwardly and toward the outer 90 end of the cylinder 10 thereby forming a contracted mouth 16 from which the wall flares outwardly as shown in Fig. 1.

This outwardly flaring portion of the wall 15 is provided with a plurality of annular 95 grooves 17 having shoulders facing the contracted mouth 16.

Threaded to the outer end of the cylinder 10 is a closure 18 with a shoulder 19 thereon bearing against the end face of said cylinder.

Into the closure 18 is threaded a tubular member 20 the inner end 21 of which is cone-shaped and provided with a plurality of large perforations 22.

Removably mounted upon said cone-shaped end 21 is a cone-shaped screen 23 of fine mesh which may be removed when de-

sired in order to clean the same or in order to replace it with another screen of a different mesh, it being obvious that for different materials different screens are desirable, and 5 even for the same material under different conditions.

The outer wall of the cone-shaped end 21 is preferably substantially parallel with the serrated or grooved wall portion of the discharge opening and separated therefrom leaving an annular passage 24, the outer end of which communicates with the annular groove 25 in the inner end of the closure 18.

Radial passages 26 from said groove 25 15 communicate with pipes 27 having valves 28 therein, the opposite ends of said pipes communicating with the annular pipe 29 surrounding the closure 18 all as shown in Fig. 2.

From the annular pipe 29 extends a pipe 30 through which the unstrained material may be returned to the interior of the cylinder 10.

The plastic material may be delivered to 25 the interior of the cylinder in any well known manner and by means of the revoluble screw 12 this stock is forced through the contracted mouth 16 into the annular passage 24 between the water cooled chamber 13 and the fine meshed screen 23 on the cone-shaped support 21.

The size of the annular passage 24 may be varied by rotating the tubular member 20 by means of the head 31 thereby moving 35 the cone-shaped end 21 inwardly or outwardly as desired. As the material passes through the passage 24 the outer portions thereof will be retarded by the shoulders of the grooves 17 while that portion of the 40 stock next to the screen will be moved faster.

This results in the cooling medium in the chamber 13 strengthening the outer portion of the material while the inner portion thereof next the screen 23 will retain its 45 putty-like consistency.

As a consequence of this unequal forward movement of the material due to one portion thereof being retarded in its movement while the inner portion moves much faster 50 than the retarded portion, any lumps that there may be in the stock are torn apart and broken up while at the same time all impurities on the screen 23 are pushed forward and off said screen thus automatically cleaning 55 said screen.

All impurities and lumps will pass the entire length of the annular passage 24 into the groove or chamber 25 from which they may be conveyed through the pipes 27, 29 60 and 30 into the interior of the cylinder 10.

The valves 28 are adapted to regulate the passage of the material returning to the cylinder.

By raising the temperature of the medium 65 in the chamber 13, the lumps will not be

broken up, but will be forced out from the passage 24 with the impurities and can be collected for separate treatment.

Heretofore the plastic material has been forced through the screen in a direction 70 perpendicular to said screen and the screen soon becomes clogged with the impurities lodged in the openings in said screen and over the surface thereof.

By making the screen cone-shaped the 75 putty-like stock may be easily forced through the fine mesh of the screen 23 and then through the perforations 22 of the cone-shaped support 21 to be finally discharged through the tubular member 20 80 while the impurities and lumps will be carried down the surface of the cone into the overflow pipes as heretofore described.

This makes a most effective strainer the 85 screen of which will be automatically cleaned by the material as it is forced outwardly through the annular passage 24.

The screens may be quickly changed thereby preventing the loss of time which has formerly been incurred in other styles 90 of strainers.

By giving the fine mesh screen a rigid 95 perforated backing the breaking of or injury to the screens is effectually overcome.

Where the material is forced directly 95 toward a screen disposed transversely of the path of movement of the material, said material is liable to be churned and overheated thereby causing an enormous decrease of tensile strength and elasticity in 100 the rubber. These objections are wholly obviated when the device herein shown and described is used.

By providing a means for breaking up or removing of all lumps from the material, 105 the material is more uniform and the tensile strength and elasticity thereof is greatly increased.

It is believed that the operation of the invention and its many advantages will be 110 thoroughly understood without further description.

Having thus described my invention, I claim:

1. In a device of the class described, a discharge tube having a contracted passage terminating in a flaring conical mouth, the wall of which is provided with a plurality of annular serrations; means for forcing plastic material into said tube; and a cone-shaped 115 screen positioned in the mouth of said tube.

2. In a device of the class described, a discharge tube having a contracted passage terminating in a flaring conical mouth the wall of which is provided with a plurality of annular material-retarding shoulders; means for forcing plastic material into said tube; and a cone-shaped screen positioned in the mouth of said tube. 120

3. In a device of the class described, a dis- 130

charge tube having an outwardly flaring cone-shaped mouth; means for forcing plastic material into said tube; a hollow cone-shaped support in said mouth removed and disconnected from said forcing means and provided with a plurality of perforations through its wall, the outer face of which is substantially parallel with, but separated from the wall of said cone-shaped mouth; and a removable cone on said support open only at one end and having a plurality of perforations therein smaller than those in said support.

4. In a device of the class described, a discharge tube having an outwardly flaring cone-shaped mouth surrounded by a chamber adapted to contain a temperature regulating medium; means for forcing plastic material into said tube; a hollow cone-shaped support in said mouth having a clear passage from its peak to its open outer end and provided with a plurality of perforations through its wall, the outer face of which is substantially parallel with but separated from the wall of said cone-shaped mouth; and a removable cone on said support having a plurality of perforations therein smaller than those in said support adapted to be removed endwise from said support.

5. In a device of the class described, a discharge tube having an outwardly flaring cone-shaped mouth; means for forcing plastic material into said mouth; a cone-shaped screen in and separated from the wall of said mouth by an annular passage; and means on the wall of said mouth for retarding that portion of the material adjacent thereto.

6. In a device of the class described, a discharge tube having an outwardly flaring cone-shaped mouth; means for forcing plastic material into said mouth; a cone-shaped screen in and separated from the wall of said mouth by an annular passage; means on the wall of said mouth for retarding that portion of the material adjacent thereto; and means for collecting that portion of the material passing entirely through said annular passage and returning it to the source of supply.

7. In a device of the class described, a discharge tube; a cup-shaped member threaded thereto and provided with an annular chamber; a cylindrical member threaded to said cup-shaped member and provided with a perforated cone-shaped end extending into

said tube and forming therewith an annular passage communicating with said chamber; a system of piping communicating with said chamber whereby the material in said chamber may be returned to its source of supply; and means for forcing material into said tube.

8. In a device of the class described, a discharge tube, a cup-shaped member threaded thereto and provided with an annular chamber; a cylindrical member threaded to said cup-shaped member and provided with a perforated cone-shaped end extending into said tube and forming therewith an annular passage communicating with said chamber; a system of piping communicating with said chamber and leading to the source of supply; means for regulating the discharge through said system of piping; and means for forcing material into said tube.

9. In a device of the class described, a discharge tube; a cup-shaped member threaded thereto and provided with an annular chamber; a cylindrical member threaded to said cup-shaped member and provided with a perforated cone-shaped end extending into said tube and forming therewith an annular passage communicating with said chamber; an annular pipe surrounding said cup-shaped member; radial pipes leading from said chamber to said annular pipe; a pipe leading from said annular pipe to the source of supply of said material; and means for forcing said material into said tube.

10. In a device of the class described, a discharge tube; a cup-shaped member threaded thereto and provided with an annular chamber; a cylindrical member threaded to said cup-shaped member and provided with a perforated cone-shaped end extending into said tube and forming therewith an annular passage communicating with said chamber; an annular pipe surrounding said cup-shaped member; radial pipes leading from said chamber to said annular pipe; a valve in each radial pipe; a pipe leading from said annular pipe to the source of supply of said material; and means for forcing said material into said tube.

Signed by me at 4 Post Office Sq., Boston, Mass. this 6th day of February, 1918.

HANS RICHARD HAERTEL.
